(57) **CLAIM**

The ornamental design for a tire inflator, as shown and described.

DESCRIPTION

This design patent application is related to United States Design Patent application Ser. No. 29/635,578, filed concurrently with this design patent application.

FIG. 1 is a front perspective view of a first embodiment of a tire inflator showing the claimed new design;

FIG. 2 is a rear perspective view of a first embodiment of the tire inflator showing the claimed new design;

FIG. 3 is a front elevational view of the tire inflator of FIG. 1;

FIG. 4 is a rear elevational view of the tire inflator of FIG. 1;

FIG. 5 is a left side elevational view of the tire inflator of FIG. 1;

FIG. 6 is a right side elevational view of the tire inflator of FIG. 1;

FIG. 7 is a top plan view of the tire inflator of FIG. 1; and, FIG. 8 is a bottom plan view of the tire inflator of FIG. 1. The dot-dash lines represent boundaries of the claimed design. The dot-dash lines depict environmental subject matter that forms no part of the claimed design. The broken lines in the drawings depict portions of the tire inflator that form no part of the claimed design. The broken lines and unshaded regions bounded by broken lines form no part of the claimed design.
